MASS SPECTROMETER

Alfred O. C. Nier and Mark G. Inghram, New York, N. Y., assignors to the United States of America as represented by the United States Atomic Energy Commission

Application September 20, 1944, Serial No. 554,965

12 Claims. (Cl. 250—41.9)

1

The present invention relates to a mass spectrometer, more specifically, it relates to a mass spectrometer suitable for analyzing gases or isotopes of gases of low atomic weight, for example, hydrogen and deuterium, and being adapted to analyze either a single gas or isotope, or two gases or isotopes simultaneously.

In the past, the relative abundance ratio of two light gases or isotopes has customarily been determined by placing a sample of the composite gases or isotopes in a mass spectrometer, analyzing it, first with respect to one of the gases or isotopes and then with respect to the others, that is, measuring successively the respective ion currents produced by the separate gases or isotopes at the collecting electrode, and thereafter comparing the two separately collected ion currents to determine the abundance ratio. In such relative abundance determinations, errors in measurement were introduced by virtue of the fact that the intensity of the electron source beam was not exactly the same during the two separate analyses of the respective gases.

Another outstanding objection to mass spectrometers used in the past is the very cumbersome, large external magnet used to bend the ion beam for purposes of focusing the beam onto a collector electrode. Large solenoids have been used, costing several hundred dollars for materials alone, and requiring a steady source of power of several kilowatts, hence requiring the use of extremely large batteries or generators with special compensators for the purpose of maintaining a constant magnetic field. Such apparatus has been cumbersome, expensive to build, as well as expensive to operate. Another difficulty present in mass spectrometers used in the past is that of developing a sufficiently intense ion beam and properly projecting and focusing such ion beam so that a high percentage of the ion current developed at the source can be focused onto the collecting electrode with minimum loss or scattering such as caused by the emission of secondary electrons along the tubular walls and slotted plates used for collimating and focusing.

An object of our invention is to provide a mass spectrometer that is devoid of the above-mentioned disadvantages and difficulties and that is

2

suitable for analyzing one or two gases or isotopes either singly or simultaneously.

A further object of our invention is to provide a mass spectrometer of simple and relatively inexpensive construction that is capable of analyzing light gases or isotopes thereof with a comparatively high degree of resolution.

Other objects and advantages will become more apparent from the study of following 10 specification, taken together with the drawings in which:

Fig. 1 is a schematic diagram of a mass spectrometer embodying the principles of our invention;

15 Fig. 2 is an enlarged perspective view of the permanent magnet located at the center of the tube shown in Fig. 1; and

Fig. 3 is an enlarged perspective view of the 20 collecting electrodes shown in Fig. 1.

Referring more specifically to Fig. 1 numeral 1 denotes a vitreous tube such as, for example, glass, the extreme ends of which are not shown. In the right portion of tube 1, as illustrated, there is provided a source of electrons comprising the 25 following combinations of elements: a tungsten filament 2 in the form of a hair pin supported by a pair of lead-ins 3, only one of which appears in Fig. 1. Lead-ins 3 extend through a glass stem 4 fused to the right extremity of tube 1 (not shown).

Upon the glass stem 4 is mounted a plate 5 having a slit 6, plate 5 being adjustably mounted to move axially on glass stem 4 so as to make it possible to precisely align the filament and slit 6. All of the above-described parts 30 2 to 6, inclusive, constitute an assembly well-known in the art. This assembly is inserted into tube 1 between a pair of spaced discs 7 and 8 of nonmagnetic material, such as, for example, a composition of nickel and chromium containing approximately 80 per cent nickel and 20 per cent chromium.

Discs 7 and 8 are inter-connected both electrically and mechanically and constitute a shield 7—8 or enclosure for the ionizing space. Plate 9 constitutes one of the inter-connecting means between discs 7 and 8 and includes a slit 6a with which slit 6 is brought into 35 registry. Also internally of the shield 7—8 is provided an electron collecting electrode 10, for example, in the form of a cup consisting of a composition containing approximately 80 per

40

45

50

cent nickel and 20 per cent chromium, adapted to collect a large portion of the electrons emitted by filament 2 as a beam, and collimated by slits 6 and 6a.

An ion repelling electrode 11 is positioned back of the electron beam, and has a potential applied thereto which is slightly more positive than that applied to shield 7-8, for example, in the neighborhood of 2 volts more positive than the voltage on 7-8. Filament 2 has a voltage that is more negative than the shield voltage while catcher electrode 10 has a voltage that is more positive than the shield voltage, thereby accelerating the electron beam toward the catcher electrode. A capillary leak 12 is provided constituting a glass tube with a capillary at the end thereof for the purpose of introducing a sample of the gas or gases to be analyzed into the space adjacent the electron beam and repelling electrode 11. As a result of electron bombardment of the gas molecules positive ions will be formed in the space enclosed by shield 7-8. A small permanent magnet, for example, of the horseshoe type, having poles 13 and 14, is provided externally of tube 1 in order to produce a magnetic field parallel to the electron beam for the purpose of collimating and aligning the electron beam so that most of the electrons will be collected by the collecting electrode 10. The ion repelling electrode 11 having a slightly positive voltage with respect to shield 7-8 would normally in the absence of the magnetic field produced by the magnet poles 13-14 attract electrons. However, in the presence of the magnetic field the electrons travel in a substantially helical path between the filament 2 and the collecting electrode 10, thus producing more ions than if they merely traveled in a straight path through the gas. If a sample of gas containing, for example, hydrogen and deuterium, is introduced through capillary leak 12, HD^+ ions having a mass of 3 as well as D_2^+ ions having a mass of 4 will be created as a result of electron bombardment of the molecules of these gases. For example, small traces of ions of mass 3 are formed with large numbers of ions of mass 4. The ion repelling electrode 11 will repel the ions in a direction at right angles to the electron beam, that is, in a direction to project the ions through a slit S1 in disc 8.

In order to accelerate the ions produced, in a direction longitudinally of tube 1, as shown by dotted lines, a pair of spaced semi-circular beam centering plates 15 and 16, having a slit S2 therebetween, have applied thereto an average voltage that is more negative than that of shield 7-8. To further accelerate positive ions, shield 7-8 has applied thereto a voltage that is substantially more positive than the voltage applied to a slotted disc 17 having a slit S3. Such voltage applied to shield 7-8 may be, for example, of the order of +360 volts whereas the disc 17 may be at zero or ground potential. The voltage applied to beam centering plates 15 and 16 is selectively adjustable from 0 to $\frac{1}{3}$ of the total accelerating voltage, that is the voltage below the voltage of shield 7-8, and is generally of the order of +330 volts. The ion beam is therefore successively accelerated through tube 1. Disc 8 and beam centering plates 15-16 together constitute an electronic lens that tends to focus the ion beam to a small extent, thus insuring entry of the ion beam through slit S3 in plate 17. The main purpose of beam centering plates 15-16, however, is that of adjustably cen-

tering the ion beam so that it will be in registry with slit S3. This can be effected by any well-known potential varying means (not shown) that can be used for the purpose of varying either or both of the voltages applied to the respective beam centering plates 15 and 16. For example, if it is found that the ion beam impinges on a portion of the disc 17 to the right of slit S3, then by making the voltage applied to plate 16 slightly more positive or by making the voltage applied to plate 15 slightly more negative, or by simultaneously varying these voltages in the manner stated, the ion beam can be made to come into registry with slit S3. The slit S3 may be of any suitable dimension, for example, 1 millimeter by 14 millimeters (the larger dimension being at right angles to the plane of the drawing).

The ion beam, after emerging from slit S3 is projected substantially coaxially of tube 1 through a V shaped analyzer comprising a cylindrical tube 18 of non-magnetic material, such as, for example, a composition containing approximately 80 per cent nickel and 20 per cent chromium, a permanent magnet M, and a metallic tube 19 (of substantially rectangular cross-section) and of non-magnetic material, such as, for example, a composition consisting of approximately 80 per cent nickel and 20 per cent chromium.

The specific construction of the permanent magnet M is shown more clearly in Fig. 2 and comprises, for example, a plurality of substantially U shaped permanent magnet portions 20 having common parallel wedge-shaped pole faces 21 and 22 made of any suitable magnetic material, such as, for example, iron or a magnetic composition including approximately 8 per cent aluminum, 14 per cent nickel, 24 per cent cobalt, and 3 per cent copper and iron. Permanent magnet portions 20 may be secured to the pole faces 21-22 by means of metallic strips 23 acting as hangers, closely surrounding the periphery of the permanent magnet portions 20, and having their extremities secured to pole faces 21-22 by suitable fastening means, such as, for example, screws 24. The upper edges of pole faces 21-22 are inter-connected by means of a thin rectangular plate 25 of a composition consisting of approximately 80 per cent nickel and 20 per cent chromium. For example, such plate is fastened to the upper edges of pole faces 21 and 22 by suitable fastening means, such as, for example, screws 26. By virtue of the above-described construction of permanent magnet M, it is possible to provide a magnetic field of relatively high intensity, for example, one having almost 1,000 gauss. The magnetic intensity can be varied by varying the number of permanent magnet portions 20 affixed to the pole faces 21 and 22. It will be noted that magnet M is totally enclosed in tube 1, hence pole faces 21-22 may be brought close together to give a strong field.

Referring to Figs. 1 and 2, it will be noted that the lateral, inclined edges of pole faces 21 and 22 form substantially a wedge. The angle formed by the lateral, inclined edges is preferably of the order of 60°. As the positive ions enter in the space partly defined by the right, inclined edges of pole faces 21 and 22, they come under the influence of the magnetic field developed by permanent magnet M, such field being perpendicular to the plane of the drawing. The magnetic field will cause bending of the ions through an arc having a radius of substantially r centimeters from the point of intersection of the 60°

disposed dashed lines in Fig. 1, and will cause sorting of ions in accordance with their different mass-to-charge ratios, that is m/e ratios. Those of larger mass-to-charge ratios will not be deflected as much as those of lighter mass, that is, they will move through a radius slightly larger than r . In view of the fringing of the magnetic field at both of the inclined edges of pole faces 21 and 22, it is necessary to consider the magnetic fields as extending beyond these edges. A suitable allowance is made when the width of the air gap between the pole faces is added to both the inclined edges as shown by dash lines in Fig. 1, which lines constitute the effective magnetic field boundaries as distinguished from the actual boundaries of the magnet M. As shown, a preferable angle between these effective boundaries is 60°.

It is known that for a slightly divergent beam of ions having the same momentum and projected into a uniform magnetic field, if the ions enter the magnetic field perpendicular to the pole boundary and are bent through such an angle in the field, as to leave the field boundary perpendicularly, then there will be a refocusing of the ions. The nature of the focusing will be such that the entrance slit S₃ of the analyzer, the apex A of the V formed by extending the effective edges of the magnetic field boundaries, and the exit slit will all lie in a straight line. It should be understood that the 60° is merely a convenient angle and is in no way critical for the purpose of focusing ions. For example, the angle between the effective laterally inclined edges of the pole faces may be anywhere between a very small angle up to an angle of 180° so long as the ion beam both enters and leaves the inclined edges of the magnet perpendicularly. It will be noted that the objections to a very small angle are that the distances of the exit and entrance slits from the edges of the magnet will be relatively great necessitating a long tube and analyzer. The provision of such long tube has not only the disadvantage of being more cumbersome but has the additional danger of providing a greater probability of scattering of the ions, by collision with other ions or neutral molecules, particularly if there is an appreciable pressure of the gas in the tube. On the other hand, by making the angle very large, for example, almost 180°, there will be practically no distance between the inclined edges of the magnet and the entrance and exit slits. In other words, the slits can be located laterally, close to the upper surface of the 180° magnetic field. Large angles, however, have the advantage of causing greater lateral separation at the collector of gaseous ions of different mass or isotopes in cases where two of these are collected simultaneously by a pair of collecting electrodes. Such large angles are particularly useful in separating elements of relatively high mass and relatively small mass difference, for example, in separating mass U²³⁵ from mass U²³⁸, whereas small angles are more suitable for the separation of elements of light mass, such as for example, for separating deuterium molecular ions having a mass of 4 from hydrogen molecular ions of mass 2 or in separating deuterium from HD⁺ ions having a mass 3.

Referring to Figs. 1 and 3, after the ions are bent by the magnetic field and separated and sorted in accordance with their different mass-to-charge ratios, they will emerge from the magnetic field tending to form two ion beams as shown in dotted lines in the case where the sam-

ple includes two gases, such as hydrogen and deuterium having different masses. One of the beams having D₂⁺ ions of mass 4 is collected by collecting electrode 27 and the other having HD⁺ ions of mass 3 by a collecting electrode 28. Collecting electrodes 27 and 28 may be supported at the left extremity of the tube 1 (not shown) and are positioned so as to be in registry with exit slits 29 and 30 located at the end of tube 19. 10. Plate 32 is provided to act as a barrier for separating collecting electrodes 27 and 28. By applying voltage to plate 31 that is more negative than the voltage of the collector electrodes 27 and 28, secondary electrons that tend to emerge from collecting electrodes 27 and 28 when bombarded by ions, are prevented from emerging from these electrodes. A suitable negative potential to apply to plate 31 is one that is, for example, about 20 volts more negative than the voltage of the 20 collecting electrodes 27 and 28, although a wide range of negative voltages may be used instead, with varying restraining effects insofar as secondary emission is concerned. The danger of secondary electron emission is that the current carried by such electrons will cause erroneous ion current readings at the collecting electrodes. The purpose of plate 32 is to prevent travel of any secondary electrons or ions that might occur in the vicinity of one collecting electrode from traveling to the vicinity of the other collecting electrode thereby introducing errors in the ion current measurement and the relative abundance ratio measurement. The ion currents collected by collecting electrodes 27 and 28 may be measured by any suitable well-known electronic means (not shown). For example, the ion current to the collecting electrode 27, which is the mass 4 collector, may be detected and measured by an electrometer of any well-known type, particularly one having, for example, a highly sensitive amplifier tube commercially known as the FP-54 type. Collecting electrode 28, the mass 3 collector, may have connected thereto either an electrometer or preferably a negative feed-back 45 amplifier (not shown) consisting of a tube commercially known as the 959 type. In order to make comparisons of currents collected by the respective collecting electrodes easier a null method or potentiometer resistor method of comparison of the collected ion currents may be used as shown in copending application Serial Number 548,588 of Alfred O. C. Nier and Edward P. Ney entitled "A Mass Spectrometer System" filed August 8, 1944, now Patent No. 2,456,426. Such 50 electronic circuits form no part of the present invention.

In the design of the apparatus shown in Fig. 1, the following well-known formula is noted:

$$\frac{m}{e} = 4.82 \times 10^{-5} \times \frac{H^2 r^2}{V}$$

where r is the radius of curvature of ions in centimeters in the magnetic field, where m is the mass of the ion in atomic mass and units and e is its charge in terms of the electronic charge as a unit, where H is the magnetic field intensity of the magnet in gauss, and where V is the total accelerating potential in volts. In separating mass 60 from mass 3 for example, the value m/e may be taken as the average of these two masses, namely 2.5, and if r is 5 centimeters and H is 1,000 gauss then $V=482$ volts, which is the accelerating voltage necessary for focusing the aforementioned values of m/e . Actually H in the

present device is less than 1,000 gauss, giving a value of V of 360 volts. By holding the magnetic field intensity constant and by adjusting voltage V various values of m/e will fit the focusing conditions and register on the designated collecting electrodes 27 and 28.

The analyzer may be assembled in tube 1 in the following manner: tube 1, being substantially Y shaped, is provided with open ends at all the extremities of the Y. Magnet M is then inserted through the lower leg of the Y and may be held in place in tube 1 by suitable flexible supporting means such as spring clips 33 and 34. The lower leg of the Y is then sealed. Tube 18 is then introduced through the right leg of the Y shaped tube 1 and by means of a long screw driver tube 18 may be fastened to the right inclined edge of magnet M by means of screws 35 that enter threaded holes at the right inclined edge of the magnet M. By means of a pair of pins (not shown) located along the periphery of the collar portion 37 of tube 18 and corresponding slots in the magnet, it will be possible to readily align screws 35 with their respective screw threaded holes in the magnet. In a similar manner, tube 19 is introduced from the left extremity of the Y shaped tube 1 and may likewise be fastened to the magnet by means of screws 38 and pin and slot connections. Of course, after suitable baking of the analyzer for purposes of degassing, as is well-known in the art, the extremities of the tubes may be sealed, that is, of course, after the remainder of the ion source assembly and collecting electrode assembly is introduced in the tube 1. A suitable vacuum is produced by means of a mercury diffusion pump (not shown) having a Dry Ice trap (not shown) that is effective to create a vacuum of about 2×10^{-7} millimeters of mercury.

It will be seen, therefore, that we have provided a mass spectrometer that is suitable to analyze either a single gas or isotope thereof, or a pair of gases or isotopes simultaneously by the use of either one or both of the collecting electrodes, respectively. By simultaneously collecting ions of two gases or isotopes there is no danger of introduction of error due to variations in ion intensity inasmuch as both readings are taken simultaneously at a single ion current intensity. It is not important whether such intensity varies from time to time because of the fact that the readings are taken simultaneously at a given ion intensity and thus will give an accurate indication of the relative abundance ratio of the two different ions representing the two different gases or isotopes. It will also be seen that by virtue of the use of beam centering plates that have the dual function of accelerating the ions as well as the function of centering the ion beam by suitably adjusting the respective voltages of the beam centering plates, we are able to accurately project a narrowly collimated beam of ions longitudinally through the entrance slit of the analyzer. Furthermore, by the provision of a permanent magnet structure that is wholly enclosed within the glass tube walls, we have provided a relatively narrow air gap through which the ion beam travels, and therefore obtain a relatively high intensity of magnetic field. Thus we have provided a relatively simple, rugged and inexpensive magnet requiring no power supply or current regulating means such as is necessary in the common external electromagnet generally used for mass spectrometers. For example, the cost of

external magnets may be several hundred dollars as compared to a few dollars for an internal permanent magnet according to our invention. It will also be noted that we have provided a relatively simple, rugged and efficient mass spectrometer that is particularly adapted for the analysis of two gases of light atomic weight simultaneously in order to determine their relative abundance ratio without error as the result of fluctuations in electron intensity of the source or the like.

It should also be noted that we have provided a mass spectrometer that despite its simplicity of construction has a substantially high resolving power for the determination of the abundance ratio of gases having light atomic weights such as deuterium and hydrogen.

It will be apparent that modifications will be readily suggested to others skilled in the art as the result of the teaching of our invention, hence, it should be understood that our invention is not limited by the specific construction hereinbefore described, which is merely an exemplary embodiment, and should be restricted only insofar as set forth in the following claims.

What is claimed is:

1. A mass spectrometer comprising an evacuated tube enclosing, in combination, an ion source at one end of said tube, means for accelerating and focusing ions from said ion source and separating them in accordance with their different mass-to-charge ratios including a permanent magnet wholly contained inside and intermediate the ends of said tube, means at the other end of said tube for collecting said ions, and two tubular non-magnetic members supported on said accelerating and focusing means, one extending in the direction of said ion source and the other extending in the direction of the ion collecting means, said members enclosing a major portion of the path of the ions.

2. A mass spectrometer comprising an evacuated tube enclosing, in combination, a source of positive ions at one end of said tube, electrode means for accelerating ions developed by said source, permanent magnet means contained wholly in said tube intermediate the ends thereof for bending and focusing said ions and separating the ions in accordance with their different mass-to-charge ratios, collecting electrode means at the other end of said tube for collecting said ions, and two non-magnetic tubular members supported on the magnet means, one extending in the direction of the ion source, and the other extending in the direction of the collecting means.

3. A mass spectrometer comprising an evacuated tube enclosing, in combination, an ion source at one end of said tube, electrode means for accelerating ions from said source, and for projecting them in the form of an ion beam, a permanent magnet of substantially U-shaped cross-section contained wholly within and intermediate the ends of said tube and having wedge-shaped poles disposed with respect to said ion beam to bend said ion beam through a predetermined angle and effect focusing thereof, a collecting electrode at the other end of said tube for collecting said focused ion beam, and two non-magnetic tubular members supported on the magnet, one member extending in the direction of the ion source, and the other member extending in the direction of the collecting electrode, said tubular members substantially enclosing the path of the ions.

4. A mass spectrometer comprising an evacuated tube enclosing, in combination, an ion source at one end of said tube, electrode means for accelerating ions from said source, and for projecting them in the form of an ion beam, a plurality of permanent magnets wholly contained within and intermediate the ends of said tube and having a common pair of confronting wedge-shaped poles for bending and focusing said ion beam, and two non-magnetic tubular members supported by the magnetic poles, one of said members extending in the direction of the ion source substantially enclosing the path of the ions to the poles, and the other of said members extending from the poles along the path of the ions and substantially enclosing said path.

5. A mass spectrometer comprising an evacuated, substantially Y-shaped tube enclosing in combination, a source of positive ions at one extremity of the Y, electrode means for accelerating ions from said source and for projecting them in the form of an ion beam along one leg of the Y, a permanent magnet wholly contained within said tube at the intersection of the Y, and projecting into a second leg of the Y and having spaced parallel wedge-shaped poles between which said beam passes for bending, projecting and focusing said ion beam into a third leg of the Y, a collecting electrode at the extremity of said third leg of the Y for collecting the ion beam, and two non-magnetic tubular members supported by the magnet poles, one of said members extending from the magnet down one leg of the Y toward the source of ions, and the other of said members extending down the other leg of the Y toward the collecting electrode.

6. A mass spectrometer comprising an evacuated tube enclosing, in combination, an ion source for simultaneously developing ions of two elements of different atomic mass, electrode means for accelerating said ions, a permanent magnet contained wholly within said tube for providing a magnetic field substantially at right angles to the direction of movement of said ions to effect bending and focusing of said ions in the form of two ion beams laterally separated in accordance with the different mass-to-charge ratios of ions constituting said two separate ion beams, a pair of collecting electrodes arranged side by side for simultaneously collecting said two ion beams, each of said ion beams being focused on one of said collecting electrodes, and two non-magnetic tubular members supported by the permanent magnet, one of said tubular members extending from the magnet toward the ion source and the other of said tubular members extending from the magnet toward the collecting electrodes, said tubular members substantially enclosing the path of the ions.

7. A mass spectrometer comprising an evacuated vitreous tube enclosing in combination, a substantially V-shaped analyzing tube of non-magnetic material, an ion source at one extremity of the V-shaped analyzing tube for projecting ions through one leg of the V-shaped analyzing tube, a permanent magnet of substantially U-shaped cross-section having wedge-shaped poles between which said beam passes and forming the juncture of said V-shaped analyzing tube for bending the ions into the form of a beam and projecting the beam through the other leg of the V-shaped analyzing tube, said permanent magnet being contained wholly within said vitreous tube, and a collecting electrode at the other extremity of said V-shaped analyzing tube.

8. A mass spectrometer comprising an evacuated vitreous tube enclosing, in combination, a substantially V-shaped analyzing tube of non-magnetic material, an ion source at one extremity of the V-shaped analyzing tube for projecting ions through one leg of the V-shaped analyzing tube, a permanent magnet of substantially U-shaped cross-section having wedge-shaped poles between which said beam passes and forming the juncture of said V-shaped analyzing tube for bending the ions into the form of a beam and projecting the beam through the other leg of the V-shaped analyzing tube, said permanent magnet contained wholly within said vitreous tube, and a pair of collecting electrodes disposed side by side at the other extremity of said V-shaped analyzing tube.

9. A mass spectrometer comprising an evacuated envelope totally enclosing in combination, means within said envelope for establishing a magnetic field, a source of ions, means projecting ions from said source in the form of a beam through said magnetic field at right angles to the lines of force thereof, said magnetic field having a cross sectional pattern to cause said beam to be resolved into components each having ions of different mass-to-charge ratio, means for selectively collecting the ions of said components and ion shielding means attached to the means for establishing a magnetic field and substantially enclosing the trajectory of the ions between the ion source and the collecting means.

10. A mass spectrometer comprising an evacuated tube enclosing in combination, an ion source at one end of said tube, electrode means for collecting ions at the other end of said tube, magnetic means between said ion source and said electrode means being wholly within said tube and having wedge-shaped pole-faces on opposite sides of the ion trajectory between said source and electrode means, and two non-magnetic tubular members supported on said magnetic means one extending in the direction of said ion source and the other in the direction of said electrode means to enclose the major portion of the path of ions between said source and said electrode means.

11. A mass spectrometer comprising an evacuated envelope generally of Y-shape, enclosing in combination, an ion source at the closed end of one arm of said envelope, an ion collecting electrode at the closed end of the opposite arm of the Y-shaped envelope, magnetic means wholly enclosed within the intermediate arm of said envelope developing a magnetic field normal to the ion trajectory, and a non-magnetic tubular element attached to said magnetic means extending into each of said first mentioned two arms of said envelope to enclose the principal length of the ion trajectory between said source and said collecting electrode.

12. A mass spectrometer comprising in combination, an evacuated tube, an ion source mounted in one end of the evacuated tube, ion collecting means mounted at the other end of the tube, means to establish a magnetic field normal to the path of the ions between the source and collecting means intermediate the ion source and the collecting means, and two non-magnetic tubular members mounted in the tube, one of said members being mounted between the ion source and the magnetic means, the other of said members being mounted between the collecting means and the magnetic

11

means, said members substantially enclosing the ion trajectory.
